LINE GUIDE FOR FISHING RODS

Edward J. Golec, Chicago, Ill., assignor to Sears, Roebuck and Co., Chicago, Ill., a corporation of New York

Filed July 5, 1963, Ser. No. 75,684

Term of patent 14 years

(Cl. D31—4)

Fig. 2.

Fig. 1.

FIG. 1 is a side elevational view of a line guide for fishing rods showing my new design, and

FIG. 2 is an end elevational view of the same taken from the left thereof as seen in FIG. 1.

The undisclosed end portion of the article is substantially plain except for the circular openings as indicated in FIG. 2.

I claim:

The ornamental design for a line guide for fishing rods, substantially as shown and described.
